UNITED STATES PATENT OFFICE

VERN G. ELLEN, OF MINNEAPOLIS, MINNESOTA, ASSIGNOR TO THE LOUDEN MACHINERY COMPANY, OF FAIRFIELD, IOWA, A CORPORATION OF IOWA

GRAPPLING APPARATUS

Application filed June 18, 1930. Serial No. 461,966.

My invention relates to improvements in grappling apparatus designed to grapple and hold a box or a barrel, or other articles having size and weight, while being hoisted or carried to a place of deposit, and when disposed of, to be easily and speedily disconnected therefrom; and it consists primarily of a main member adapted to be connected to hoisting and carrying devices, and having 10 a number of grappling hooks pivoted to its opposite edges, whereby said hooks, of their own gravity, will come in contact with opposite sides of the articles to be handled, and also to be easily and speedily disconnected 15 and held therefrom by the movement of a subsidiary member pivoted to a central portion of the main member.

In the accompanying drawings forming a part of this specification, Fig. 1 is a slightly 20 perspective view of an apparatus embodying my invention and showing the upper end of a barrel, or other cylindrical container, attached thereto. Fig. 2 is a more pronounced perspective showing the apparatus in its disconnected position. Fig. 3 is a vertical section on line 3—3 of Fig. 1, the article to be 25 handled being removed, and the apparatus being shown in its disconnected position. Fig. 4 is a top or plan view of the main member, the grappling hooks and other principal 30 attachments being removed. Fig. 5 is a detached plan view of the subsidiary member. Fig. 6 is a vertical section of the central part 35 of the apparatus immediately surrounding an eye-bolt to which the hoisting or carrying device is to be connected.

Referring to the drawings, the main member is shown composed of a circular sheet or plate of metal A, to which two pairs of angle bars B are fastened at substantially right angles to each other, as most plainly shown in Fig. 4. One pair of these angle bars is extended centrally across the sheet A and the other pair is centrally cut apart and their inward ends are welded or otherwise secured to the central portions of the other bars.

Each of these pairs of angle bars is spaced apart with their upstanding flanges on the inner sides adjoining the spaces. Notches C 50 are cut in the edges of the sheet or plate A

between the ends of the angle bars, and holes are made in the ends of the upstanding flanges of the bars in which pins D are inserted, and on these pins the upper ends of grappling hook E are pivoted. The notches C in the edges of the plate A will permit the hooks to swing inwardly sufficiently to grapple and hold the article to be handled. Below the metal plate A, a subsidiary or hook releasing plate F is mounted, and is operated as will be hereafter explained.

In the central part of the plate A a hole is made and in between the central portions of the angle bars B a casting G having a central tubular opening is inserted, and through this opening and through the hole in the plate A an eye bolt H is passed. Below the plate a collar I is placed on the bolt. The lower end of this collar is made smaller so its upper part will act as a shoulder.

A hole is also made in the central part of the plate F to fit and turn freely on this smaller portion on the collar I. The plate F being placed in position on the collar I, the washer J is placed below it on the bolt H, and is held in place thereon by the nut K which when drawn snugly against the lower portion of the collar will leave the plate F loosely mounted on the reduced lower end of the collar, whereby it can be freely turned thereon. To prevent the nut K from working loose, a lock nut L may be added, and be provided with a cotter pin M to hold it securely in place, all of which is most plainly shown in Fig. 6.

As shown by Fig. 5, the outer edge of the subsidiary plate F is substantially circular and has recessed portions N corresponding in number with the number of grappling hooks used in the apparatus. As shown in the drawings, four grappling hooks are used but a larger number or as few as two hooks might be used. Whatever the number of hooks used the recesses N in the plate F must correspond with them. When the plate F is turned so the deepest parts of the recesses N will be opposite the hooks E, they will be free to swing inwardly, and, of their own gravity, come in contact with the article to be handled, as shown in Fig. 1.

When the plate F is turned in the opposite direction the lower ends of the hooks E will slide out on the outwardly extended portions of the plate until they reach the portions O 5 when they will be held out in disconnected position as shown in Fig. 2. To bring the hooks into engaged position with the article to be handled, all that is necessary is to turn the plate F in the direction which will bring 10 the hooks opposite the deepest parts of the recesses N. The hooks will then be free to swing inwardly of their own gravity, and engage the article to be handled. As shown in Fig. 5, the edge of the plate F which will 15 be next the operator will be turned to the right to bring the grappling hooks into the recesses N and in engagement with the article to be handled, and to the left to bring them against the parts O and to release the hooks 20 therefrom, but if desired, it may be constructed to catch and release said article by turning it in the opposite directions.

To facilitate the turning of the plate F it is advisable that handles P be connected 25 thereto, preferably one on each side as most plainly shown in Figs. 1 and 2. Also, to hold the plate F most steadily in position it is advisable to form an arcuated opening R in its 30 opposite sides, as most plainly shown in Fig. 5, and attach downwardly extending bolts or pins S above to opposite portions of the main plate A, whereby the lower ends of these bolts or pins will extend down through the corresponding arcuated openings. These bolts or 35 pins should also be provided with nuts T or with other means to hold the plate F at a uniform distance from the main plate A, while it is being moved from one position to another.

40 It is advisable to have additional holes in the ends of the angle bars B for the pins D upon which the grappling hooks E are pivoted, as shown in Figures 1, 2 and 3, whereby the hooks can be set closer together or wider 45 apart to suit different sizes of the articles to be handled. Also, when a pattern is provided, a single casting may be substituted for the plate A, angle bars B, central casting G and the collar I by making the pattern with 50 the notches C, flanges for the pivot pin holes D, its central portion to accommodate the eye bolt H, and a central downward extension in place of the collar I upon which the subsidiary plate F may be mounted. The drawings show the main part of the apparatus 55 made of material which can be secured without having a pattern for a special casting.

The apparatus is simple, is easily operated and is extremely practical in its operation.

60 Having thus described my invention, what I claim as new and desire to secure by Letters Patent is:—

65 1. In a grappling apparatus, a main member adapted to be connected to a hoisting or a carrying device, and having grappling

hooks pivoted on its opposite edges, whereby they tend to swing inward and engage and hold the article to be handled, and a subsidiary member centrally pivoted below the main member, the edges of said subsidiary member being so formed that by turning it on its pivot in one direction the hooks will be free to move inward and engage the article to be handled and by turning it in the opposite direction the hooks will be moved outward and be disconnected from said article. 70

2. In a grappling apparatus, a main member adapted to be connected to a hoisting or a carrying device, and having notches in its opposite edges, grappling hooks pivoted in said notches, and adapted to swing inward and engage and hold the article to be handled, and a subsidiary member centrally pivoted below the main member, the edges of said subsidiary member being so formed that by turning it on its pivot in one direction the hooks will be free to move inward and engage the article to be handled, and by turning it in the opposite direction the hooks will be moved outward and be disconnected from said article. 80

3. In a grappling apparatus, a main plate substantially circular in form and having notches in its opposite edges, angle bars arranged in pairs and fastened to the upper side of said plate with their ends on opposite sides of the notches, pivot pins in the ends of said angle bars over the notches, grappling hooks pivoted on said pins and adapted to swing inward and engage and hold the article to be handled, and a subsidiary plate, approximately circular in form and with recesses in its opposite edges, centrally pivoted to the under side of the main plate and adapted to be turned thereon, whereby the grappling hooks will be permitted to swing inward when the subsidiary plate is turned with the recesses opposite the hooks and when said plate is turned in the opposite direction the hooks will be held outward in disconnected position. 90

4. In a grappling apparatus, a main plate substantially circular in form and having notches in its opposite edges, angle bars arranged in pairs and fastened to the upper side of said plate with their ends on opposite sides of the notches, pivot pins in the ends of said angle bars over the notches, grappling hooks pivoted on said pins and adapted to swing inward and engage and hold the article to be handled, a subsidiary plate, approximately circular in form and with recesses in its opposite edges, centrally pivoted to the under side of the main plate and adapted to be turned thereon, whereby the grappling hooks will be permitted to swing inward when the subsidiary plate is turned with the recesses opposite the hooks, and 100 105 110 115 120 125 130

when said plate is turned in the opposite direction, the hooks will be held outward in disconnected position, and handles connected to the subsidiary plate to assist in turning it.

In witness whereof, I have hereunto subscribed my name.

VERN G. ELLEN.
